(57) **CLAIM**

The ornamental design for a mat connector, as shown and described.

DESCRIPTION

FIG. 1 is a perspective view of mat connector showing my new design;

FIG. 2 is a top perspective view of the male portion of the claimed design;

FIG. 3 is a bottom perspective view of the male portion of the claimed design;

FIG. 4 is a top perspective view of the female portion of the claimed design;

FIG. 5 is a bottom perspective view of the female portion of the claimed design; and,

FIG. 6 is a cross-sectional view of the mat connector fully assembled.

The broken line showing is for illustrative purposes only and forms no part of the claimed design.

The elements of the claimed design have been shown separately for ease and clarity of illustration.

The claimed design is shown broken away to indicate indeterminate length.
